UNITED STATES PATENT OFFICE

DALLAS C. MOFFETT, OF LOGAN, OHIO

DRILL CABLE SNAP OR CRACKER

Application filed June 15, 1932. Serial No. 617,416.

The invention relates to a snap or cracker device for use in the drilling of wells, such as oil wells, gas wells or water wells of any depth with cable tools.

5 The primary object of the invention is the provision of a device of this character wherein the same is adapted for use between a string of cable drilling tools and a wire drilling line to impart the necessary flexibility, springiness and snap necessary for fast drilling and to eliminate the terrific shocks and jars incident to the operation of the drilling tools by transmission to the drilling machinery through the wire line.

10 It is a fact in the art of well drilling that to obtain best results the drilling tools must be thrown into engagement with the earth with percussive force, or in other words, the cable must have a necessary amount of "snap" or possess a certain elastic quality during the drilling operation and also to allow the cable to stretch and rebound and thus giving to the tools the percussive action required.

15 Another object of the invention is the provision of a device of this character, wherein its construction assures to the tools the required snap or cracker action so called and also to assure the required flexing and absorption of shocks and jars incident to the drilling operation, the device being of novel form and is readily attachable to a string of cable drilling tools and a wire drilling line.

20 A further object of the invention is the provision of a device of this character, wherein its construction is such as to assure longevity and maximum wearing quality, as well as strength and durability, without liability of inefficiency in the quick drilling operation for the drilling of oil, gas and water wells of any depth with cable tools and is susceptible of manufacture at a minimum cost.

25 With these and other objects in view, the invention consists in the features of construction, combination and arrangement of parts as will be hereinafter more fully described in detail, illustrated in the accompanying drawing, which discloses the preferred embodiment of the invention, and pointed out in the claims hereunto appended.

30 In the accompanying drawing:—

Figure 1 is an elevation of the device constructed in accordance with the invention.

Figure 2 is a fragmentary enlarged side elevation partly in section showing in detail the make-up of the device.

55

Figure 3 is a sectional view on the line 3—3 of Figure 2.

60

Similar reference characters indicate corresponding parts throughout the several views in the drawing.

Referring to the drawing in detail, the device is indicated generally at A and includes a solid rubber core 5 of any required length preferably approximately twenty-five feet in length and at its tapered end 6 receives therein the wire drilling line 7 of an oil drilling machine, the end 8 of this line 7 embedded in the core 5 being centrally located and is anchored therein at 9.

65

Applied to the core 5 externally of the same is a wrapping of two layers of strong cord 10 and 11 respectively, these being disposed in their wrapped condition in opposite directions to each other and such layers of strong cord are carried throughout the major length of the core 5, that is, from the tapered end 6 to the opposite end of the same. A protective covering 12, preferably of rubber, envelops the layers of cord 10 and 11 and this covering or coating of rubber is vulcanized

70

with the cords 10 and 11 therein similar to an automobile tire shoe or casing with the result of longevity, maximum wearing quality, elasticity and efficiency in the device for use as a snap or cracker between the wire drilling line 7 and a string of cable drilling tools for association therewith.

75

The protective covering 12 at its end remote from the tapered end 6 of the core is formed with a flared or bulged head or terminal 13 for accommodation in a separable coupling 14 for the connection of the device with a string of cable drilling tools.

80

In the use of the device the desired or required snap is present during the operation of the drilling tools so as to accomplish a percussive force upon engagement of the drilling tools with the earth in the making of a well and also shocks and vibrations or jars are eliminated between the drilling tools

95

100

and the drilling machinery in that such shocks and jars cannot be transmitted to the latter through the wire drilling line which results in increased wear to such machinery and also ease of operation thereof. By the use of the device constructed as heretofore stated it eliminates the necessity of the use of a large amount of manila rope which is commonly used with the drilling tools to give the same the required flexibility.

There will be little wear on the device on account of its being relatively short as comparable with substitutes and its extreme flexibility tends to keep the slack line tightened up at all times which will result in a great deal less wear on the wire line above the device. This device assures a drilling operation with dispatch and will enable the tools to strike harder as more of the force of the blow will be transmitted to the work and less to the line.

What is claimed is:—

1. A device of the character described comprising a solid straight resilient core, two-ply wrappings of fibrous cord about the core, a protective coating enveloping the wrappings and vulcanized thereto, the said wrappings being reversely extended, and a wire drill line anchored in one end of the core, said protective coating being enlarged at the end of the core to form a head remote from the anchorage of the line.

2. A device of the character described comprising a solid resilient core, fibrous wrappings about the core, a protective coating enveloping the wrappings and vulcanized thereto, the said wrappings being reversely extended, and a wire drill line anchored in the core at one end thereof, the protective coating being enlarged at the end of the core to form a head remote from the anchorage of the line.

In testimony whereof I affix my signature.

DALLAS C. MOFFETT.
